United States Patent Office.

FREDERICK SCHAEFFER, OF PHILADELPHIA, PENNSYLVANIA.

Letters Patent No. 96,038, dated October 19, 1869.

IMPROVED APPARATUS FOR DIVIDING POWDERS.

The Schedule referred to in these Letters Patent and making part of the same.

To all whom it may concern:

Be it known that I, FREDERICK SCHAEFFER, of Philadelphia, Pennsylvania, have invented an Improved Apparatus for Dividing Powders; and I do hereby declare the following to be a full, clear, and exact description of the same.

My invention consists of an apparatus, fully described hereafter, for rapidly and accurately dividing masses of powder into a number of equal portions, it being useful for many purposes, but being especially intended for dividing medicinal powders into small quantities suitable for packing in papers, the apparatus, when used for this purpose, enabling the medicine to be packed without handling, and without any of the usual measuring or weighing.

In order to enable others to make and use my invention, I will now proceed to describe the mode of constructing and using the same, reference being had to the accompanying drawing, which forms a part of this specification, and in which—

Figures 1 and 2 are perspective views of the two main portions of my improved apparatus for dividing powders;

Figure 3, a plan view of the apparatus, showing the two portions fitted together;

Figure 4, a transverse section on the line 1-2, fig. 3;

Figure 5, an inverted plan view of fig. 2; and

Figures 6 and 7, detached perspective views of parts of the invention.

Similar letters refer to similar parts throughout the several views.

A represents the box-like frame of the apparatus, consisting of a bottom piece, *a*, back piece, *b*, and opposite side pieces, *c c*, the latter being furnished on the outside with suitable handles, *d*, by means of which the apparatus can be readily lifted, when it is to be moved from place to place.

On the inner side of each of the side pieces *c c*, and close to the upper edge of the same, is a horizontal groove, *f*, and crossing this groove at points adjacent to the back piece *b*, are two or more vertical grooves, *h*.

These latter grooves *h* are arranged to receive the opposite ends of a strip, *i*, the lower edge of which rests upon the bottom *a*, a space, *j*, being thus enclosed, of greater or less capacity, according as the grooves which receive the ends of the strip are adjacent to or remote from the back piece *b*.

The horizontal grooves *f*, of the side pieces, are adapted for the reception of the tongued ends of a slide, *b*, which is provided with a suitable handle, *k*, and has secured to its under side a number of wedge-shaped blocks, *m*, the latter being of equal size, arranged at regular distances apart, and being in contact with the bottom piece *a* when the slide is fitted to the grooves *f*.

The method of using the apparatus is as follows:

If but a small quantity of powder is to be placed in

each package, the strip *i* is fitted to those grooves *h* which are nearest to the back piece *b*, or if a greater quantity is required, the strip is moved forward, so as to increase the capacity of the space or powder-receptacle *j*. (See figs. 1 and 4.)

The powder to be divided is then poured into the receptacle, and is distributed evenly throughout the same, and levelled by means of a toothed rake, similar to that shown in fig. 6, these rakes being of different sizes, according to the position of the strip *i*, and consequent width of the powder-receptacle. After this the slide *B* is moved close up to the strip *i*, as shown in fig. 4, and the latter is then withdrawn vertically from its grooves *h h*, the motion of the slide being next continued toward the back piece *b*, until it has assumed the position shown in fig. 3.

This latter movement of the slide, after the withdrawal of the strip *i*, causes the sharp wedge-shaped ends of the blocks *m* to penetrate the mass of powder contained in the receptacle *j*, and to divide the same into as many equal portions as there are spaces between the blocks, all that next remains to be done being to turn the entire apparatus upon one end, in such a manner that the powder thus evenly divided may be caused to flow from the funnel-shaped spaces *x* (see fig. 5) into the papers into which it is to be packed.

To repeat the operation, the slide is drawn back, and the strip *i* reinserted, the powder being then introduced, divided, and ejected in the same manner, until a sufficient quantity has been packed, the operation being both rapid and accurate, and requiring none of the usual handling, weighing, or measuring.

In cases where a smaller number of packages than are usually filled by the apparatus is to be put up, simple blocks of wood, such as are represented in fig. 7, and of sufficient length to cover one or more of the spaces between the wedge-shaped blocks, may be introduced into one end of the powder-receptacle.

I claim, as my invention, and desire to secure by Letters Patent—

1. The box *A*, open at one side, and having a bottom, back, and side pieces, *a*, *b*, and *c*, the latter being furnished with horizontal and vertical grooves *f* and *h*, adapted to receive slides *B* and *i*, all substantially as and for the purpose herein described.

2. The combination of the said box *A* with the slide *B*, when the latter is furnished with wedge-shaped blocks *m*, arranged at regular distances apart, substantially as herein set forth.

In testimony whereof, I have signed my name to this specification, in the presence of two subscribing witnesses.

FRED. SCHAEFFER.
